UNITED STATES PATENT OFFICE.

MORTON L. JOHNSON, OF CHICAGO, ILLINOIS, ASSIGNOR TO FRANK B. COOK COMPANY,
OF CHICAGO, ILLINOIS, A CORPORATION OF ILLINOIS.

TELEPHONY.

1,236,569.

Specification of Letters Patent. Patented Aug. 14, 1917.

Application filed June 29, 1914. Serial No. 847,824.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of 10 this specification.

My invention relates to telephone exchange systems wherein link connectors are provided each having operator controlled means at one end for connection with calling 15 lines and preferably at the other end for connection with called lines. My invention preferably includes means whereby subscribers may select such link connectors for use, and preferably provides for the selection of 20 an idle link selector which is preferably controlled by the calling subscriber.

I will explain my invention more fully by reference to the accompanying drawings showing the preferred embodiment thereof 25 and in which Figure 1 is a diagrammatic view illustrating the invention as simply as possible; Fig. 2 is a view illustrating the manner in which Figs. 3, 4 and 5 are to be assembled in order that they may be read in 30 connection with each other; and Figs. 3, 4 and 5, when assembled as indicated in Fig. 2, indicating, in diagrammatic detail, one form of telephone exchange system equipped in accordance with the invention.

Referring first more particularly to Fig. 1, I have there diagrammatically indicated two substations, 90, 95, which extend to the exchange where they are provided with selector switches A. Similarly positioned waiting contacts of these selector switches are multiplied and the different groups of these multiplied waiting contacts are individual each to different operators' positions generally indicated at B where the operators are 45 provided with telephone outfits C. Each group of waiting contacts is also individual to a selector switch D, similarly positioned waiting contacts of these selector switches D being multiplied and the different groups of 50 these latter multiplied waiting contacts are individual each to a different link connector E. Each of these link connectors E terminates at both ends in operator controlled terminals which are here shown in the form

of wipers constituting parts of connector 55 switches F, F¹, though the invention is not to be limited to the nature of the terminals provided for the link connectors E. When connector switches F, F¹ are provided each waiting contact of each is individual to a 60 telephone line of a group, all the telephone lines of such group having waiting contacts in each switch F. The system illustrated is of a hundred line capacity, it being understood that if a larger system is employed 65 that selector switches would intervene between the switches D and F. When the connector switches F, F¹ are employed the operator is equipped with keys G, H for effecting the operation of such connector switches, 70 these keys G, H being connected with the selector switches D when the associate operators' telephones are connected with the calling lines that have become connected with such switches D. In establishing connection 75 the calling subscriber will remove his telephone from its switch hook, thereby setting the wipers of his selector switch A into operation until such wipers encounter the waiting contacts pertaining to an idle operator 80 B, whereupon the wipers will stop in connection with the telephone C of the selected operator and the selector switch D individual to the selected operator whereupon the selector switch D that has become connected 85 with the calling line will have its wipers set into operation until they become connected with the waiting contacts pertaining to an idle link connector E after which the selected operator will manipulate her switching apparatus G H to bring the connector switches F, F¹ of the selected link connector E into connection with the calling and called lines to establish connection therebetween.

Referring now more particularly to Figs. 95 3, 4 and 5, at each of the substations 90 and 95 I have illustrated well known telephone equipment that includes a telephone transmitter 1, telephone receiver 2, a call bell 3, a condenser 4, and a telephone switch hook 100 5, the telephone switch hooks serving, when supporting the receivers, to open the telephone bridges at the substations. The bell and condenser at each substation is shown as being included in permanent bridge of 105 the associate telephone line. When a call is initiated the calling subscriber will metallically connect the sides 6 and 7 of his line

by the establishment of his telephone bridge whereby a circuit is established which may be traced from the grounded battery 8 (which may be common to the exchange), the upper winding of the line relay 9 of the calling line, the intermediate armature switch of the cutoff relay 10 and its contact, the line side 6 of the calling line, the telephone bridge at the calling station, the line side 7 of the calling line, the bottom armature switch of the cutoff relay 10 and its contact, to the lower grounded winding of said line relay 9. The line relay is thereupon energized to establish a circuit traceable from its lower grounded armature switch, the contact of this switch, the bottom armature switch of the switching relay 11 and its contact, the winding of motor magnet 12, the interrupter 13, to the 20 grounded battery 8. By reason of the interrupter 13 the circuit of magnet 12 is intermittently established whereby its armature occasions the step by step movement of the ratchet wheel 14 upon the shaft 15, on 25 which shaft the wipers 16, 17 and 18 of the selector switch A belonging to the calling line are mounted. The wipers of the operating switch A are turned until the wiper 18 engages an ungrounded waiting contact 30 that pertains to an idle operator and an idle switch D. As the wiper 18 passes over grounded contacts circuit is established and maintained which is traceable from the grounded contact connected with the wiper 35 18, through the wiper, the uppermost armature switch of the private control relay 19 and its engaged contact, the upper winding of this relay 19, to the grounded battery 8, the relay 19 being energized each time the 40 armature of the motor magnet 12 is energized by a circuit traceable from the grounded battery 8, the lower winding of relay 19, the armature of magnet 12 and the contact engaged thereby, to ground. When 45 the wiper 18 engages an ungrounded waiting contact the circuit previously traced through the upper winding of relay 19 is no longer maintained whereby the relay 19 is deenergized when the armature of the driving magnet is restored to normal whereby the armature switches of relay 19 are released. The lowermost armature switch of 50 relay 19, when released, engages its grounded contact to establish a circuit traceable from this contact and its armature switch, through the lower armature switch of relay 20 and its engaged contact (relay 20 having previously been energized by a circuit traceable from the lower grounded armature 55 switch of relay 9 and its contact, the winding of relay 20, the intermediate armature switch of relay 19 and its engaged contact, to the grounded battery 8, the circuit for this magnet 20 being maintained by the 60 locking circuit established by the circuit 65

traceable from the grounded battery 8, the upper armature switch of relay 20 and its engaged contact, the winding of relay 20, the lower armature switch of relay 9 and its engaged contact, to ground), the winding of relay 11, to the grounded battery 8. The relay 11 being thus energized, its lower armature switch opens the circuit of the motor magnet 12 to stop the rotation of the wipers 16, 17 and 18 and its two upper armature switches engage their contacts to connect the two wipers 16, 17 respectively with the sides 6 and 7 of the calling line. The calling line is now connected with an idle operator at a non-busy position C and having 70 telephone equipment B. This telephone equipment is included in circuit with the calling line owing to the energization of the switching relay 21, there being one such relay 21 for each operator's position, this relay at a selected operator's position being energized for the purpose of including the telephone at the selected operator's position in circuit, the energizing circuit of the relay being traceable from the grounded battery 8, the operator controlled release key 22 (for restoring the selected operator's telephone equipment to its normal open circuit condition) the winding of relay 21, the wiper 18 and the waiting contact engaged 80 thereby, the lowermost armature switch of relay 11 and its alternate contact, the lower armature switch of relay 9 and its engaged contact, to ground. The selected operator's telephone set is now in circuit with the calling line and the selected operator ascertains the number of the line wanted. When an operator's outfit is selected the selector switch D individual to such operator is also selected and is set into motion to select an 85 idle link E. This result is due to the circuit established at the lowermost armature switch of relay 21, which circuit is traceable from the grounded contact of this armature switch, the armature switch, the winding of relay 23, to the grounded battery 8, the left hand and grounded armature switch of relay 23 establishing a circuit traceable from this armature switch, through the contact thereof, the winding of sluggishly operating 90 interrupter relay 24 the armature switch of this relay and its engaged contact, the winding of motor magnet 25, the side switch wiper 26 of the selected switch D in the first position of this side switch wiper, to the 95 grounded battery 8. Due to the energization of the motor magnet 25, wipers 27, 28, 29, 30, 31 and 32 continue in operation until wiper 29 engages an ungrounded waiting contact whereupon circuit for the private 100 magnet 33 is opened to cause the side switch wipers 26, 34 and 35 to step into their second positions, the circuit for the motor magnet 25 being consequently opened at the side switch wiper 26. The side switch wiper 105 110 115 120 125 130

26, in its second position, establishes an obvious circuit for the relay 36, the upper armature switch of relay 36 connecting the key G with the wiper 28 while the lower armature switch of relay 36 connects the key H with the wiper 31. Before the operator manipulates the keys or switching mechanism G, H, the operator depresses the key or switch 37 to establish a circuit through the relay 38 traceable from the grounded contact of the key 37 through the key, the winding of relay 38, the key or switch 22 individual to the key 37, to the grounded battery 8, the relay 38 establishing an obvious locking circuit through itself that includes its lower grounded armature switch and its engaged contact. The upper grounded armature switch of relay 38 engages its contact to preserve the circuit for relay 21 that also includes the aforesaid key 22. By this means the ground established at the lower armature switch of relay 9 by way of the wiper 18 upon the employed relay 21 is replaced by the ground at the upper armature switch of relay 38 whereby the previously employed selector switch A may be released by mechanism to be described before the operator establishes connection between the calling and called lines.

30 The selected operator will now manipulate the key G to move the wipers 39, 40 and 41 belonging to the switch F until the wipers 39 and 40 engage waiting contacts pertaining to the calling line and the wiper 41 engages a contact individual to the calling line and pertaining to a local circuit at the exchange that includes the cutoff relay 10 through a circuit traceable from the grounded battery 8, the winding of the cutoff relay 10, the arrested wiper 41 and the contact then engaged thereby, the side switch wiper 42 in its third position, the upper armature switch of the sluggishly operating relay 43 and its engaged contact, to ground whereby the calling line is cleared from the selector switch A individual thereto.

The operation of the connector switch F, which is employed to connect the calling line with the selected link E, is as follows:

50 It will be remembered that, when relay 36 was operated by the moving of side switch wiper 26 into its second position, a circuit was established for the operation of line relay 47. This circuit is as follows: Grounded battery, upper winding of relay 47, upper contact and armature switch of relay 48, armature switch and upper contact of relay 62, wiper 27 of switch D, normally closed contacts of key or switching apparatus G, upper armature switch and contact of relay 36, wiper 28 of switch D, lower outside contact and switch armature of relay 62, intermediate armature switch and contact of relay 48, lower winding of

relay 47 to ground. The operation of relay 47 prepares a circuit which will be utilized in connection with the subsequent operation of the vertical motor magnet 44. In the operation of line relay 47, relay 43 is operated by an obvious operating circuit completed through the lower armature switch and contact of relay 47. The operation of relay 43 in turn establishes a circuit which will result in the operation of the vertical motor magnet 44 when the switching mechanism G is operated to send the series of vertical impulses. This circuit is as follows: Grounded battery, side switch wiper 51, vertical motor magnet 44, winding of relay 46, contact and armature switch of relay 43, thence to lower contact of relay 47. Relays 43 and 46 are of the sluggish type and therefore will remain in an operated position while the relay 47 is rapidly operated by the breaking and making of its circuit at the switching mechanism G. As the circuit is intermittently ruptured at the switching mechanism G, relay 47 will be intermittently operated, thus intermittently completing the operating circuit just described at the lower armature switch of relay 47. The result of this operation is to place the wipers of switch F before the level of contacts in which the calling line is to be found.

The operation of relay 46 establishes a circuit for the energization of the private magnet PM, which magnet, when released, serves to move the side switch wipers 51 and 42 from their first to second position, thereby establishing a circuit to rotate the switch F to the contacts pertaining to the calling line. The circuit for the operation of the private magnet may be traced as follows: Grounded battery, winding of private magnet PM, upper armature switch and contact of relay 46 to ground. Relay 46 will be de-energized and open the circuit of the private magnet when the relay 47 becomes continuously operated at the end of the series of vertical impulses transmitted by means of switching mechanism G. As previously stated, the de-energization of the private magnet moves the side switch wipers and establishes the circuit for receiving the rotary impulses. This circuit is as follows: Grounded battery, private wiper 51 (now in its second position), winding of rotary motor magnet 45, intermediate armature switch and contact of busy relay BR, winding of relay 46, thence by circuit as previously described for the vertical operation of switch F. The proper manipulation of switching mechanism G will now rotate the wipers 39, 40, and 41 of switch F into connection with the waiting contacts of the calling line. During the rotary operation of the switch, the private magnet will have been again energized and under the control of relay 46, 130

as previously described. The release of the private magnet will move the side switch wipers 51 and 42 to their third position, thereby establishing the circuit for the operation of cut-off relay 10, the operating circuit of which already has been described.

The side switch wiper 51 in its third position provides a circuit for the operation of the switching relay 48. The operation of this relay extends the talking circuit of the connector through to the switch wipers 39 and 40 and disconnects the line relay 47. The circuit may be traced as follows: Grounded battery, switch wiper 51, winding of relay 48 to upper armature switch of relay 43¹ associated with connector switch F¹, thence to the grounded contact, relay 43¹ at this time being energized through a circuit similar to that already described for relay 43 of switch F. The ground established through the upper armature switch and contact of relay 43¹ also serves to maintain the circuit for the operation of cut-off relay 10 after relays 47 and 43 of switch F have been deenergized.

The operator will next manipulate the key or switch H to operate the connector F¹ to connect the called line with the selected link connector thereby to complete the connection between the calling and called lines. The operations previously described in connection with switch F follow in connection with the operation of the switch F¹, it being unnecessary to repeat this description, it being, however, stated that parts of switch F¹ that are similar to correspondingly operating parts of switch F are given characters of reference similar to those applied to such corresponding parts of switch F with prime exponents added. The connector F¹, since it pertains to the called line, is provided with the additional equipment that connector switches usually have and which enable the impression of signaling current upon called lines and the manifestation of a busy test if the desired line is busy. The ringing and testing equipment supplied by the switch F¹ is of the usual kind and includes the ringing generator 52, the ringing relay 53, the ringing interrupter 54, and the armature switches 55 of the ringing relay 53. The busy tone producing equipment includes the interrupter 56, the induction device 57, etc. The connector switch F¹ also has the talking side switch wipers 58 and 59, the private cutoff relay 60, and the back bridge relay 61. There are added to the described equipment of switches F, F¹ relays 62 and 62¹ having similar functions and which are controlled by the relay 63 common thereto; this relay in turn being controlled by the key 22. The relay 63, having had its circuit established through the side switch wiper 35, of switch D, in second position and the associate wiper 30 then engaging the waiting

contact individual to the relay 63, was energized to open its armature switch. When key 22 is depressed the locking circuit for relay 38 is opened to open the circuit of relay 21 to open the circuit of relay 23. When relay 23 is opened its right hand armature switch closes the circuit for the release magnet 64 of the employed switch D, the off normal switch 65 of switch D having been closed. The switch D is consequently restored to normal whereby the circuit of relay 63 is opened at the side switch wiper 35 and the wiper 30 of switch D, which wipers are now restored to normal. The armature switch of the now deenergized relay 63 establishes a circuit traceable from the grounded battery 8, through the armature switch of relay 63, the winding of relay 62¹, the winding of relay 62, the upper armature switch of the sluggishly operating relay 43¹ to ground. The windings of relay 47¹ are now placed in bridge of the calling line by a previous path. When the called party answers the windings of relay 61 are placed in bridge of the called line whereby these relays are respectively placed in control of the calling and called lines, relay 43¹, being jointly controlled by relays 47¹ and 61 is deenergized when the calling and called parties restore their telephones upon their switch hooks. The deenergized relay 43¹, in the usual manner, closes circuit through the release magnet 49 to restore the switch F¹ to normal. When relay 43¹ is deenergized the ground previously placed by its previously attracted upper armature switch upon the relay 48 is removed from such relay to deenergize it whereupon the lowermost armature switch of relay 48 closes circuit through the release magnet 49 to restore the connector switch F to normal.

While I have herein shown and particularly described the preferred embodiment of my invention I do not wish to be limited to the precise details of construction and circuit arrangement shown as changes may readily be made without departing from the spirit of my invention, but having thus described my invention I claim as new and desire to secure by Letters Patent the following:

1. A telephone exchange system including telephone lines; a plurality of link connectors each provided with an operator controlled electro-magnetic switch at each end to connect the same with lines; and calling subscriber controlled selector mechanism for selecting free link connectors.

2. A telephone exchange system including telephone lines extending to an exchange having a plurality of operators' positions; link connectors common to the operators' positions and each provided with an operator controlled electro-magnetic switch at each end to connect the same with lines; and

- calling subscriber controlled link connector
selectors for selecting free link connectors.
3. A telephone exchange system including
telephone lines extending to an exchange
5 having a plurality of operators' positions;
link connectors common to the operators'
positions and each provided with an opera-
tor controlled electro-magnetic switch at
one end to connect the same with calling
10 lines; and calling subscriber controlled link
connector selectors for selecting free link
connectors.
4. A telephone exchange system including
telephone lines extending to an exchange
15 where there are a plurality of operators'
positions; a plurality of link connectors each
provided with operator controlled means at
both ends to connect the same with lines;
calling subscriber controlled selector
20 switches for selecting free link connectors;
and selector switches governed by calling
subscribers for selecting idle operators and
idle link selector switches.
5. A telephone exchange system including
25 telephone lines extending to an exchange
where there are a plurality of operators' positions;
a plurality of link connectors each
provided with operator controlled means at
both ends to connect the same with lines;
30 selector switches for selecting three link
connectors; and selector switches governed

by calling subscribers for selecting idle op-
erators and idle link selector switches.

6. A telephone exchange system including
telephone lines extending to an exchange 35
where there are a plurality of operators' po-
sitions; a plurality of link connectors each
provided with operator controlled means at
one end to connect the same with calling
lines; calling subscriber controlled selector 40
switches for selecting free link connectors;
and selector switches governed by calling
subscribers for selecting idle operators and
idle link selector switches.

7. A telephone exchange system includ- 45
ing telephone lines extending to an exchange
where there are a plurality of operators'
positions; a plurality of link connectors
each provided with operator controlled
means at one end to connect the same with 50
calling lines; selector switches for selecting
free link connectors; and selector switches
governed by calling subscribers for selecting
idle operators and idle link selector switches.

In witness whereof, I hereunto subscribe 55
my name this thirteenth day of June, A. D.
1914.

MORTON L. JOHNSON.
